EMERGENCY RELEASE FOR ELECTRIC
SWITCH LOCKS

William C. McWhirter, Wilkinsburg, Pa., assignor
to The Union Switch & Signal Company, Swiss-
vale, Pa., a corporation of Pennsylvania

Application December 12, 1945, Serial No. 634,560

9 Claims. (Cl. 70—346)

1

My invention relates to an emergency release for electric switch locks.

As is well known, electric switch locks are commonly provided for the control of outlying switches which are operable by a manual lever, and they function to prevent operation of the lever away from its normal position except when the lock is released. The locking of the lever is usually effected by means of a dog controlled by an electromagnet and cooperating with a locking segment operatively connected with the lever, while the releasing of the lock is normally effected by energizing the electromagnet over a control circuit controlled from a distant point such as a signal tower, a telegraph station or a signal.

With locks of this type it sometimes happens that the usual means for releasing the lock fails due for example to a failure in the source of power for the control circuit, a break in the control circuit due to storms, etc., and one object of my invention is to provide novel means for releasing the lock under these conditions.

Another object of my invention is to provide emergency release means which can be operated by the usual switch padlock key, but not until after a telltale device, such as a standard car seal, is broken to visibly indicate to the proper officials that an emergency release has been effected.

Another object of my invention is to provide latch means which is effective when the emergency release means are operated to latch the lock in its unlocked position until a maintainer subsequently operates the latch to permit the lock to return to its normal locked position.

According to one form of my invention, the emergency release mechanism is mounted on the inside of the lock mechanism in such manner that to insert the key into the release mechanism it is necessary to lift a swinging cover, and this mechanism comprises a lifter block effective when lifted to raise the locking dog out of the notch in the locking segment. The lifter block is operated by a lifter spring which, in turn, is operated by the key. The lifter spring provides a means whereby proper release of the lock dog may be obtained by switchman's keys having varying degrees of wear and stroke, and limits the force or strain it is possible to apply to the lock mech-

2

anism by the key, whereby damage to the lock mechanism due to excessive force is prevented. The lifter block may be shaped so that it also functions as a key register, and is further provided with means cooperating with the key which insures its return to the normal position before the key can be withdrawn from the release mechanism. A telltale to show operation of the release mechanism is obtained by providing a standard car seal which must be broken before the swinging cover can be rotated to the position to insert the switch key.

In a modified form of my invention the means on the lifter block, which cooperates with the key to insure the return of the lifter block to its normal position before the key can be removed from the mechanism, is omitted, and the lifter block is provided with means which cooperates with a spring biased latch in such manner that, when the lifter block is lifted to the position in which it raises the locking dog out of the notch in the locking segment, the latch will engage the lifter block and subsequently retain it in its lifted position until a maintainer subsequently operates the latch to permit the lock to return to its normal locked position.

Other objects and characteristic features of my invention will become apparent as the description proceeds.

Locks provided with emergency release mechanism embodying my invention are an improvement upon those shown and described in Letters Patent of the United States No. 1,126,834, granted to W. P. Neubert and W. E. Smith on February 2, 1915, for Electric switch locks.

The present application is a continuation-in-part of my prior application, Serial No. 533,709, filed on May 2, 1944, for Emergency release for electric switch locks.

I shall describe two forms of emergency releases for electric switch locks embodying my invention, and shall then point out the novel features thereof in claims.

In the accompanying drawings, Fig. 1 is an end view of an electric lock provided with one form of emergency release means embodying my invention. Fig. 2 is a vertical sectional view of the release means of the lock shown in Fig. 1. Fig. 3 is a sectional view taken on the line III—III of Fig. 2. Fig. 4 is a top view of the release means

shown in the preceding views. Fig. 5 is a detail view of the key guide plate 10 forming part of the release mechanism illustrated in Figs. 2 and 3. Fig. 6 is a detail view showing a modification of the mechanism as illustrated in the preceding views. Fig. 7 is a view similar to Fig. 5 showing another modification of the mechanism as illustrated in the preceding views. Fig. 8 is a top view of the release means shown in Fig. 7.

Similar reference characters refer to similar parts in each of the several views.

Referring to the drawings, the reference character 1 designates the casing of an electric switch lock which may for example be similar to that described in detail in the Neubert et al. Patent No. 1,126,834 referred to hereinbefore. Pivots mounted within the casing 1 for rocking movement about a rod 2 is a locking segment 3, the upper end of which is provided with a notch or recess 4 adapted to coact with a locking dog 5. The locking segment 3 and locking dog 5 correspond respectively to the locking plate 25 and locking dog 27 in said patent, and the locking segment is operatively connected with lever latch means which is not shown but which means is effective to prevent movement of the hand throw lever of a switch operating mechanism away from its normal position as long as the dog 5 remains in the notch 4. The dog 5 is normally adapted to be moved out of engagement with the notch 4 by means of an electromagnet not shown, the energization of which will generally be effected by a suitable control circuit controlled from a remote point such as a signal tower, a telegraph station, a signal or the like.

The portion of the switch lock thus far described is well known, and if a more detailed description of this portion is desired reference may be had to the said Neubert et al. Patent No. 1,126,834.

As was pointed out hereinbefore, in electric switch locks of the type described the electric control circuits sometimes fail, and when this happens it is desirable to be able to release the lock by suitable emergency release means in order that trains may be kept moving on or off sidings under properly authorized emergency instructions. For this purpose, I provide the improved emergency release means which I shall now describe.

As here shown, this release means comprises a suitable guide bracket 8 riveted to one wall of the casing 1 below the outer end of the locking dog 5 opposite an opening 9 in the wall of the casing. A key guide plate 10 (Figs. 2 and 5) is interposed between the bracket 8 and the adjacent wall of the casing, and is provided with a key opening 11 which aligns with a key center stud 12 secured to the bracket 5. The key opening 11 is of such shape that it will only permit switch keys of a predetermined size and shape to be placed on the key center stud, and it follows therefore that it serves as a preselecting means for the switch keys to limit the type of key which can be inserted into the release means. A key register stud 13 (Figs. 3 and 4) provided with notches 14 corresponding to that provided in the key of the desired design is also secured to the bracket 8 at one side of the key center stud 12 so that the release can only be operated by the proper key.

The switch key cooperates with a lifter spring 15 one end of which is curved around a supporting stud 16 secured to the bracket 8, and the other end of which bears against an offset por-

tion 17a formed on a lifter block 17. The lifter block is guided for vertical sliding movement between the bracket 8 and the key guide plate 10 by means of a vertical guide slot 17b which is milled in the block and which receives with some clearance the inner ends of two vertically aligned guide studs 19 secured to the bracket 8. The offset portion 17a of the lifter block carries a vertical lug 17c which cooperates with the underside of the locking dog 5. The upper position to which the lifter block is free to move is limited by engagement of a shoulder 17d provided on the lifter block below the offset portion 17a in such position that when the lifter block reaches the desired upper extreme position this shoulder will engage the key register stud 13. The lowermost position to which the lifter block is free to move is determined by engagement of the lifter spring 15 with a stop stud 20 secured to the bracket 8, which stud also serves to limit the extreme position to which the key can be rotated. The shoulder 17d in addition to serving as a means to limit the upper movement of the lifter block 17 also cooperates with the key to force the lifter block downwardly to its lowermost extreme position before the key can be rotated to the position to withdraw it from the key opening 11.

A tubular member 33 of suitable size to clear the switch keys is pressed into the opening 9, and the outer end of this member is flared outwardly and cooperates with a weatherproof pliable packing disc 21a attached to a swinging cover 21. The cover 21 is pivotally supported on the outside of the casing 1 on a pivot pin 22 mounted in spaced lugs 23, and is biased to a closed position by a coil spring 24 surrounding the pin. One end of this spring is secured to the casing 1 by means of a screw 25 and the other end engages a laterally projecting pin 26 provided on the inside of the cover. The pliable packing disc 21a is not attached directly to the cover, but instead is attached to a metallic disc 21b secured by means of a screw 30 against a ball shaped boss 21c on the cover to insure alignment of the packing disc with its seat. Foreign elements which might otherwise enter and obstruct or interfere with the proper performance of the lock mechanism are therefore shut out. The lower end of the cover is provided with a finger grip 27 to facilitate opening the cover, and cooperates with a car seal 32 looped through spaced stud projections 28 provided on the casing 1 on opposite sides of the cover, whereby when the car seal is in place the cover cannot be opened without breaking the seal.

In operation, the emergency release mechanism is only used in the event of failure of the normal release mechanism, and then only after the trainman has obtained permission to break the seal, usually by telephone communication with a central dispatcher's office. When the necessary permission is obtained, and the seal has been broken, the trainman then lifts the cover 21 by gripping the finger grip 27 and inserts the proper key 65 through the tube 33 and opening 11 in the key guide plate. In actual practice, this key will usually be the same key which is used to operate the switch padlock. Rotation of the key causes the key to engage the lifter spring 15 and force it upwardly, which upward movement, in turn, forces the lifter block to its upper position, and hence acts through the lug 17c to lift the dog 5 out of the notch 4 in the locking plate. The lifting of the dog 5 out of the notch 4 in the locking plate frees the lever latch means in the

same manner as when the dog is lifted out of the notch 4 by the electromagnet in the normal operation of the lock, and permits operation of the switch by the hand throw lever. The lifter spring 15 provides a means whereby proper release of the lock may be obtained by switchman's keys of the various degrees of wear and stroke and at the same time limits the force or strain which it is possible to apply by the key to a value which is insufficient to damage the lock. The spring may be designed to provide the necessary stroke required to lift the dog 5 clear of the notch 4 when the release is operated by keys having the maximum permissible wear, and a key with less wear or a new key will then merely deflect the spring by a slight amount after the lock dog is lifted to its released position. Before the key can be withdrawn from the release mechanism after the release has been operated it is necessary to restore it to a position in alignment with the key opening 11, and due to the stop stud 20 this can only be done by rotating the key in a direction opposite to that in which it was rotated to operate the release. During the latter part of this rotation the key will engage the shoulder 17d and force the lifter block downwardly to its lowermost position so that for future operation the lock dog 5 will be free to enter the notch 4 when the electromagnet is deenergized, and left in the normal manner under the control of the electromagnet.

Since it is necessary according to operating rules to obtain authorization to break the cover seal prior to operating the emergency release mechanism, the breaking of the seal becomes a matter of record. It then becomes the duty of the maintainer to inspect the electric lock as a whole and see that it is in proper operating condition before he reseals the key hole cover in its normally closed position. This eliminates any necessity for special keys and depositories for these keys, and permits the use with safety of the usual switch key to operate the release mechanism.

If desired the key register stud 13 can be dispensed with and the desired key register can then be formed in the shoulder 17d as shown in Fig. 6 in such manner that the key will clear the shoulder when and only when the lifter block is in its lowermost position.

While only one type of mechanism seal is shown threaded through two stud projections on the end of the casing of the electric lock to insure against operation of the cover without removal of the seal, it is obvious that other designs of seals might be similarly applied.

Referring now to Figs. 7 and 8, the emergency release means in the form here shown comprises a lifter block 40 which corresponds to the lifter block 17 of the emergency release means shown in the preceding views. The lifter block 40 is guided for vertical sliding movement in the same manner that the lifter block 17 is guided for vertical sliding movement, but instead of being provided with a shoulder which cooperates with the trainman's switch key to force the block to its lowermost position before the key can be withdrawn from the lock, it is provided with a shoulder 40a which cooperates with an L shaped leaf spring 41 to bias the lifter block to its lowermost extreme position for a purpose which will be made clear presently. The leaf spring 41 is secured as by riveting to the bracket 8.

The lifter block 40 further differs from the lifter block 17 in that it is provided on its inside edge

with key register means 40b which takes the place of the key register stud 13 shown in the preceding views, and on its outside edge with a notch 40c which cooperates with a latching finger 42a formed on the depending arm 42b of a latch 42. The arm 42b of the latch extends downwardly through a vertical slot 43 milled in a bar 44 which serves as a guide for the locking dog 5, and is pivotally supported within the slot 43 on a pivot pin 44a secured to the guide bar 44. The latch 42 is also provided with a horizontal arm 42b disposed above the upper edge of the guide bar 44. The free end of this arm is bent at right angles to the remainder of the arm and carries a depending stud 42c which serves as a guide for a compressed coil spring 45 disposed between the arm and the upper edge of the guide bar 44. The spring 45 constantly biases the latch to such a position that the latching finger 42a will enter the notch 40c in the lifter block whenever the lifter block is moved to the position in which the notch aligns with the latching finger, and the notch is so disposed that it will align with the latching finger when and only when the lifter block is moved to its upper position.

With the release means constructed as shown in Figs. 7 and 8, it will be apparent that whenever the lifter block 40 is moved to its upper extreme position by a trainman to effect an emergency release of the electric lock, the spring actuated latch 42 will automatically engage the lifter block and hold it in its upper position until the latch is subsequently manually operated to release the lifter block. Access to the latch can only be had by opening the cover of the lock, and since the maintainer is the only person that has the necessary authority to open the cover, it follows that once the lock is operated it can only be released by the maintainer. When the maintainer operates the latch to restore the lock, the lifter block will be urged to its lower or normal position by the combined forces due to gravity, the torque of the electromagnet armature, and the bias of the spring 41, and upon reaching its lower position it will permit the locking dog to return to its normal locked position.

Although I have herein shown and described only two forms of emergency releases for electric switch locks embodying my invention, it is understood that various changes and modifications may be made therein within the scope of the appended claims without departing from the spirit and scope of my invention.

Having thus described my invention, what I claim is:

1. In an electric lock for switches including the usual electrically controlled locking dog disposed within a casing and movable between a locking and a released position, the combination of emergency release means operable by the same key which is used to operate the switch padlock for at times moving said dog to its released position independently of the usual release means comprising a lifter block slidably mounted in a guide bracket secured to one wall of said casing inside of the casing opposite an opening provided in said wall, a key center stud secured to said bracket, a lifter spring pivotally attached at one end to said guide bracket and cooperating at the other end with said lifter block, said spring being positioned to be operated by a key disposed on said key center stud and effective when operated to operate said lifter block, and means attached to 75 said lifter block and effective when said block

is operated to operate said dog to its reduced position, said spring being proportioned to provide the necessary stroke required to move said dog to its released position when the release is operated by keys having a predetermined maximum permissible amount of wear, and to deflect after the dog reaches its released position when the release means is operated by keys having less wear.

2. In an electric lock for switches including the usual electrically controlled locking dog, the combination of means operable by the same key which is used to operate the switch padlock for moving said dog to a released position including a lifter block effective when operated to one position for moving said dog to its released position, and yieldable means acting to transmit force from the key to the block, said means being so constructed that said block can be operated to its one position by keys having varying degrees of wear.

3. In an electric lock for switches including the usual electrically controlled locking dog, the combination of means operable by the same key which is used to operate the switch padlock for moving said dog to a released position including yieldable means for transmitting force from the key to said dog to move it to its released position, said yieldable means being constructed to enable a predetermined release stroke to be obtained with keys having varying degrees of wear.

4. In an electric lock for switches including the usual electrically controlled locking dog disposed within a casing, the combination of emergency release means operable by the same key which is used to operate the switch padlock for at times releasing said dog independently of the usual release means comprising a lifter block slidably mounted in a guide bracket secured to one wall of said casing inside of the casing opposite an opening provided in said wall, a key center stud secured to said bracket, a key guide plate interposed between said bracket and said opening and provided with a key opening which aligns with said first mentioned opening and said key center stud, said key opening being of such shape that it will only permit switchman's keys of a predetermined size and shape to be placed on the key center stud, a key register stud secured to said bracket at one side of said key center stud to further restrict the type of key that can be used to operate said release means, a lifter spring mounted at one end on a stud secured to said guide bracket and cooperating at the other end with said lifter block, said spring being positioned to be engaged intermediate its ends by a key rotated about said key center stud and effective when engaged by a key to move said lifter block to an operated position, means attached to said lifter block for operating said dog to its released position in response to movement of said dog to its operated position, and other means on said lifter block cooperating with the key to restore said lifter block to a predetermined normal position before the key can be rotated to the position in which it can be withdrawn from the key opening.

5. In an electric lock for switches including the usual electrically controlled locking dog, the combination of means operable by the same key which is used to operate the switch padlock for releasing said dog including a lifter block effective when operated to one position for moving said dog to its released position, yieldable means acting to transmit force from the key to the block, said means being so constructed that said

block can be operated to its one position by keys having varying degrees of wear, and key register means on said lifter block for limiting operation of said block to predetermined types of keys.

6. In an electric lock for switches including the usual electrically controlled locking dog disposed within a casing and movable between a locking and a released position, the combination of key operated emergency release means for at times moving said dog to its released position independently of the usual release means comprising a lifter block slidably mounted in a guide bracket secured to one wall of said casing inside of the casing opposite an opening provided in said wall, a key center stud secured to said bracket, a lifter spring pivotally attached at one end to said guide bracket and cooperating at the other end with said lifter block, said spring being positioned to be operated by a key disposed on said key center stud and effective when operated to operate said lifter block, means attached to said lifter block and effective when said block is operated to operate said dog to its released position, said spring being proportioned to provide the necessary stroke required to move said dog to its released position when the release is operated by keys having a predetermined maximum permissible amount of wear, and to deflect after the dog reaches its released position when the release means is operated by keys having less wear, and latch means cooperating with said lifter block and effective when said lifter block is operated to the position in which said dog is released to subsequently latch said lifter block in its dog releasing position until said latch is manually operated to release said lifter block.

7. In an electric lock for switches including the usual electrically controlled locking dog, the combination of means operable by the same key which is used to operate the switch padlock for moving said dog to a released position including a lifter block effective when operated to one position for moving said dog to its released position, yieldable means acting to transmit force from the key to the block, said means being so constructed that said block can be operated to its one position by keys having varying degrees of wear, and a latch biased to a latching position and effective when said lifter block is operated to said one position to subsequently retain said lifter block in said one position until said latch is operated to release said lifter block.

8. In an electric lock for switches including the usual electrically controlled locking dog, the combination of means operable by the same key which is used to operate the switch padlock for releasing said dog including a lifter block effective when operated to one position for moving said dog to its released position, yieldable means acting to transmit force from the key to the block, said means being so constructed that said block can be operated to its one position by keys having varying degrees of wear, key register means on said lifter block for limiting operation of said block to predetermined types of keys, and a latch biased to a latching position and effective when said lifter block is operated to said one position to subsequently retain said lifter block in said one position until said latch is operated to release said lifter block.

9. In an electric lock for switches including the usual electrically controlled locking dog, the combination of means operable by the same key which is used to operate the switch padlock for releas-

ing said dog including a lifter block effective when operated to one position for moving said dog to its released position, yieldable means acting to transmit force from the key to the block, said means being so constructed that said block can be operated to its one position by keys having varying degrees of wear, a notch in said latch, and a dog biased to a latching position and provided with a latching finger adapted to enter said notch when and only when said lifter block is moved to said one position to thereby latch said

block in the one position until said latch is operated to release said block.
